PNEUMATIC WASTE COLLECTOR ON
THREAD-WORKING TEXTILE MA-
CHINESWalter Siegenthaler, Erlenbach, Switzerland, as-
signor to Maschinenfabrik Schärer, Erlenbach,
SwitzerlandApplication January 3, 1951, Serial No. 204,175
In Switzerland March 28, 1950

5 Claims. (Cl. 242—35.5)

1

My present invention relates in general to multi-head machines for spinning, twisting, winding, finishing, and dressing yarns and threads, and in particular to pneumatic clearing apparatus applicable to such machines for removing and confining dust, fluff and like waste products.

The apparatus disclosed by my present invention comprises a trap sheet disposed within the range of the moving threads and intended for collecting the dust, fluff, and the like, and a blower-operated air-conduit system for maintaining a blowing and a sucking action within the range of said trap sheet. The said system suitably is so constructed and, during operation of the machine, so moved automatically on a track that the trap sheet is periodically cleared from the accumulated waste at each operating head of the machine.

My present apparatus effectively removes fiber waste and dust from the operating head of the machine, and thus, positively prevents the accumulation of waste thereon.

Two forms of my invention, applied to a winder comprising a plurality of operating heads, are shown in the accompanying drawing, in which—

Fig. 1 shows a side elevation of a first form, partly in section,

Fig. 2 a partial top plan view thereof,

Fig. 3 a partial rear elevation as seen from the left of Fig. 1,

Fig. 4 a partial side elevation, partly in section, of a second form, and

Fig. 5 a nozzle of Fig. 4 in front elevation.

In the form shown in Figs. 1-3, a plurality of identical winders B are disposed in line on an elongated machine frame A. Each winding apparatus comprises a circular rotary element 1 keyed to a central shaft 2, to which element are secured a plurality of winding pegs 3 which are uniformly spaced circumferentially thereof and are intended to receive a pirn a each. The element 1 is rotated step by step so as to present the pirns a consecutively to an operating head in which the respective peg 3 is automatically coupled to a driving spindle (not shown), for which purpose the latter is axially movable in the casing of winder B. After the package wound upon pirn a (which subsequently is to be used in a shuttle) has reached a predetermined size, the element 1 is rotated through one step to present an empty pirn a to said head. The winders B are driven from a common motor (not shown) through an endless belt 4 which runs on two idling or reversing rollers disposed at the

5 ends of the machine frame. The belt 4 through a friction roller 5 drives the main shaft 6 of each winder B. The pirn a situated in the operating head is supplied with thread b through a brake-and-guide mechanism 7. Thread b is derived from a supply bobbin c mounted on a holder 8 which is disposed on the machine frame.

Below the supply bobbins c there is provided a 10 rearwardly ascending sheet-iron trap plate 9 which is secured to frame A and covers all the winders B. The said plate 9 on the machine frontside has an upwardly bent border 10 which is parallel to the rear border 11. The edges 10, 11 are at a higher level than a longitudinal rib 12 formed in plate 9 intermediary of said borders or edges.

A stand 13 is movable on a lower longitudinal rail 15 through two grooved rollers 14 and in an upper U-shaped longitudinal rail 17 through a 15 pair of rollers 16, the rail 17 being rigidly secured to a third rail 18 parallel thereto. All the said rails are rigidly secured to the machine frame A. The stand 13 comprises a box 19 which is subdivided into a chamber 20 and an air duct 21 of which an upward extension forms a tube 22 which extends to the machine front side and at its respective end is connected to an orifice 24 through a comparatively stiff hose 23. The orifice 24 is disposed above the trap plate 9 and terminates in a blow tube 25 and a blow nozzle 26 which has an upright rectangular mouth, both elements 25 and 26 of the orifice 24 being situated within the range of trap plate 9 and adjacent the free longitudinal edge of the front border 10 thereof. Also above the trap plate 9 is disposed an elongated orifice 27 having two parallel suction pipes 28 which protrude into the head of said chamber 20. The orifice 27 with its respective mouth is disposed parallel to the longitudinal trap-plate rib 12 and adjacent the latter. A filter bag 28' is loosely suspended in said chamber 20 and is accessible from the outside after removing a cover 29 associated with the box 19, in order to be removed from the latter and emptied. A suction port 30 of a blower 31 disposed in the foot of air duct 21 projects into chamber 20. The blower 31 is operated by an electric motor 32 secured to stand 13. The mouths of two parallel blow pipes 33 springing from air duct 21, are situated within the range of the rearward free border 11 of trap plate 9.

With motor 32 switched on, the blower 31 produces an upward air current in duct 21, the major portion of said current reaching the orifice 24 through tube 22 and hose 23 and being discharged

from said orifice through the blow elements 25 and 26. This air current is conducted on the top side of plate 9 substantially transversely toward the orifice 27 of the suction-pipe pair 28, partly impinging against the longitudinal rib 12 of plate 9 and being deflected thereby towards the orifice 27. A portion of the air current flowing upwardly in duct 21 passes through the two blow pipes 33 and then across the top side of plate 9 against the rib 12 thereof, whereby it also is deflected towards the orifice 27. Within the range of rib 12 the air currents flowing in opposite directions impinge on each other, thus giving origin to whirls whereby fluff carried in the said currents and partly moved directly on plate 9 towards the rib 12, is raised at this point towards the orifice 27. The fluff thus is effectively sucked off through the orifice 27 and the two pipes 28. Through the latter, the air current carrying the fluff flows into the head of chamber 20 formed in box 19 and downwardly through the filter bag 28' where it is cleaned and from which it flows into the suction port 30 of blower 31. In the conduit system formed by box 19 and the parts and portions associated therewith, air thus is cycled continuously whereby the catch plate 9 is cleared of fluff by virtue of the co-operation of induced-draft air and forced-draft air.

In order to clear in the manner described the catch plate 9 within the range of all the winders B, i. e. the entire top side of plate 9, the stand 13 during such clearing operation is wheeled back and forth on the rails 15 and 17 of the machine frame A so as to periodically clear all the machine operating heads of fluff. For such purpose, the stand 13 through a link 34 is connected to an endless chain 35 which is driven by the motor (not shown) which operates the machine. The chain 35 runs over idling rollers 36 (Fig. 3) which are spaced a certain distance from each other on the machine frame A. When the stand 13 has covered its operating distance, whereby it has passed slightly beyond the respective reversing roller of chain 35, the stand (after a temporary standstill) is run back, as will be readily appreciated.

In the modification shown in Figs. 4 and 5, the trap plate 37 comprises an upper marginal rib 38 on its rear border which rib replaces the longitudinal rib 12 on trap plate 9 of the first example. Within the range of rib 38 is disposed an orifice 39 of a suction pipe 40 which communicates with the chamber 20 of box 19 and forms a transverse head on the suction pipe 40. An orifice 41 is connected to hose 23 of the forced-draft air line and comprises a central blow tube 42 and two lateral blow tubes 43 (Fig. 5).

In this form of invention, the air flowing from orifice 41 through the tubes 42 and 43 across the top side of plate 37 is blown towards the marginal rib 38 of plate 37 and, thus, towards the orifice 39 of suction pipe 40. The air flows through the latter into the chamber 20 of box 19 which is fixed to the stand 13, and then through the filter bag 28' (as in the previous example) into the suction part of the blower. The construction and mode of operation of this modification otherwise are similar to those of the first example.

The stand 13 which is movably mounted on the machine frame A, may be that shown by pending application Serial Number 204,176, filed jointly by applicant and Kaspar Laager on January 3, 1951, which application discloses the

frame as carrying bobbin pay-out means which is automatically supplied by a stationary or a mobile feeder. As disclosed by said pending application, the feeder has a magazine for empty bobbins, and during its run automatically supplies empty bobbins to the individual winders as required in accordance with the winding operation or, respectively, with the automatic cop-changing motion on the winders. The machine could be so constructed that the bobbin pay-out means or stand 13 respectively, instead of moving back and forth on a track of given length, is moved unidirectionally on a closed track. In such arrangement, the bobbin pay-out means supplies empty bobbins for example to two rows of winders arranged opposite to each other on the machine frame A, the fluff suitably being removed from the two rows of winders. The machine shown and described may be varied in other details also. For example, the blower 31 instead of being driven by a separate electric motor, may be driven from the driver motor, for example directly by means of the driving belt 4.

What I claim as new is:

1. A winding machine comprising an elongated frame, a row of winding devices carried by said frame, means above said devices for supplying yarn thereto, a part positioned above said devices and below said means formed to present an upwardly facing surface for receiving lint and the like falling from the latter, a support, means mounting said support for movement along said row longitudinally thereof, a suction pipe and an air discharge pipe carried by said support having air inlet and air discharge ends, respectively, which ends are positioned above and adjacent said upwardly facing surface in opposed spaced relation transversely of said surface; suction and blower means carried by said support for drawing air through said air inlet end of said suction pipe, and for discharging air from said air discharge end of said air discharge pipe, for moving lint collecting on said upwardly facing surface toward said air inlet end of said suction pipe for removal of such lint from said part through said suction pipe.

2. A winding machine according to claim 1 in which the suction pipe includes an enlarged chamber portion containing a removable filter bag, through which latter the air being sucked by said pipe passes for removing and collecting the lint carried by such air.

3. A winding machine according to claim 1 in which the part presenting the upwardly facing surface is provided on its upper side with a longitudinally extending rib projecting upwardly from said surface and having a side thereof opposed to the air discharge end of the air discharge pipe in spaced relation thereto for directing the air discharged by said pipe and the lint moved by such air upwardly over said side, the air inlet end of the suction pipe being positioned adjacent an upper portion of said side of said rib for receiving and removing the lint so directed.

4. A winding machine according to claim 1 in which the part presenting the upwardly facing surface is provided on its upper side intermediate the width of said surface with a longitudinally extending rib presenting upwardly inclined opposite sides which converge toward a ridge as they so extend, the air discharge pipe being provided with two air discharge ends one opposed to one of said sides in spaced relation thereto and the other opposed to the other of said sides in spaced relation thereto, in each case for direct-

ing the air discharged from the air discharge end of the pipe and the lint moved by such air upwardly over said sides, the air inlet end of the suction pipe being positioned adjacent said ridge presented by said rib for receiving and removing the lint so directed.

5. A winding machine according to claim 1 in which the part formed to present the upwardly facing surface is also formed to present a pair of spaced upwardly and longitudinally extending opposed surfaces defining the width of said upwardly facing surface, the air discharge end of the air discharge pipe being positioned adjacent one of said pair of surfaces for moving lint and

the like across said upwardly facing surface toward the other of said pair of surfaces, the air inlet end of the suction pipe being positioned adjacent the upper edge of the said other of said pair of surfaces for removing such lint from said upwardly facing surface.
